US0D1036654S

(12) **United States Design Patent** (10) Patent No.: **US D1,036,654 S**
(45) Date of Patent: ** Jul. 23, 2024

(54) **TOOTH CLEANER**

(71) Applicants: **QINGDAO HAIGAO DESIGN AND MANUFACTURING CO., LTD.**,
Qingdao (CN); **SHANGHAI HAIER MEDICAL TECHNOLOGY CO., LTD.**,
Shanghai (CN); **HAIER SMART HOME CO., LTD.**, Qingdao (CN)

(72) Inventors: **Jianmei Li**, Qingdao (CN); **Ran Tian**,
Qingdao (CN); **Jingshuang Wang**,
Qingdao (CN)

(73) Assignees: **QINGDAO HAIGAO DESIGN AND MANUFACTURING CO., LTD.**,
Qingdao (CN); **SHANGHAI HAIER MEDICAL TECHNOLOGY CO., LTD.**,
Shanghai (CN); **HAIER SMART HOME CO., LTD.**, Qingdao (CN)

(**) Term: **15 Years**

(21) Appl. No.: **29/809,122**

(22) Filed: **Sep. 25, 2021**

(30) **Foreign Application Priority Data**

Apr. 2, 2021 (CN) 202130186960.2

(57) **CLAIM**

An ornamental design for the tooth cleaner, as shown and
described.

DESCRIPTION

FIG. 1 is a front elevational view of the tooth cleaner
showing the design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a first perspective view thereof; and,

FIG. 8 is a second perspective view thereof, wherein the
nozzle is stored inside.

1 Claim, 7 Drawing Sheets
